* cited by examiner

Primary Examiner — Bridget L Eland(74) Attorney, Agent, or Firm — Greenblum & Bernstein P.L.C.(57) CLAIM

I claim the ornamental design for a home gateway device, as shown and described.

DESCRIPTION

FIG. 1 is a perspective view of a home gateway device, showing my new design;

FIG. 2 is a front elevational view thereof;

FIG. 3 is a bottom view thereof;

FIG. 4 is a top plan view thereof;

FIG. 5 is a left side elevational view thereof;

FIG. 6 is a right side elevational view thereof; and,

FIG. 7 is a rear elevational view thereof.
